CLAIM

The ornamental design for a brush handle, as shown and described.

DESCRIPTION

FIG. 1 is a perspective view of a brush handle, showing my new design;

FIG. 2 is a bottom plan view thereof;

FIG. 3 is a top plan view thereof;

FIG. 4 is a right side elevation view thereof;

FIG. 5 is a left side elevation view thereof;

FIG. 6 is a front elevation view thereof; and,

FIG. 7 is a rear elevation view thereof.

The evenly spaced broken lines in the drawings depict portions of the brush handle that forms no part of the claimed design. The dot-dash broken lines in the drawings depict the boundary of the claim that forms no part of the claimed design.
